UNITED STATES PATENT OFFICE.

HENRY E. TITUS, OF PLAINFIELD, NEW JERSEY.

DESIGN FOR A FRAME FOR SHOE-POLISHERS.

SPECIFICATION forming part of Design No. 27,504, dated August 10, 1897.

Application filed June 9, 1897. Serial No. 640,079. Term of patent 3½ years.

To all whom it may concern:

Be it known that I, HENRY E. TITUS, a citizen of the United States, and a resident of Plainfield, in the county of Union and State of New Jersey, have invented a certain new and original Design for a Frame for Shoe-Polishers, of which the following is a specification, reference being had to the accompanying drawings, forming part thereof.

10 Figure 1 is a top view of a frame for a shoe-polisher embodying my new design. Fig. 2 is a side view.

As shown in the drawings, the leading feature of my design is the handle proper, A, in 15 the center of the frame, shaped as shown.

The ends B at each extremity of the frame are similarly bent and shaped, as shown.

Having described my invention, what I claim as new, and desire to secure by Letters Patent, is—

20 The design for the frame of a shoe-polisher, as herein shown and described.

Signed at New York, in the county of New York and State of New York, this 8th day of June, A. D. 1897.

HENRY E. TITUS.
